SHIPPING AND DISPLAY CARTON

Albert H. Koeble, Irvington, N. J., assignor to The
United States Printing & Lithograph Co.,
New York, N. Y., a corporation of Ohio

Application November 1, 1934, Serial No. 751,059

1 Claim. (Cl. 206—44)

This invention relates to improvements in so-called "knock-down" cartons or paper enclosures and has more particular relation to improvements in the type of cartons that are employed 5 both for shipping purposes and afterwards for display purposes.

One of the principal objects of the invention is to provide a shipping carton of limited area so constructed that when received it may be adjusted for a display stand having an extended firm base line for supporting articles of merchandise in elevated and distributed positions.

A further object of the invention is to provide a "knock-down" shipping carton so constructed 15 that when received with the merchandise, its form may be entirely changed to convert it into a display stand for the merchandise, and destroy its outline as a shipping carton.

A still further object of the invention is to 20 provide a "knock-down" shipping carton which when received may be adjusted for display purposes with a display shelf in elevated position.

The invention also has other objects, all of 25 which will be hereinafter more particularly designated.

In the drawings,

Figure 1 represents a top plan view of the cardboard blank after the same has been cut and scored.

30 Figure 2 represents a front elevation of the carton assembled ready to receive contents for shipping.

Figure 3 represents a top plan view of the carton assembled after its receipt, to function as a 35 display stand.

Figure 4 represents a front elevation of the device as assembled in Figure 3.

Figure 5 represents a top plan view of the upper display shelf.

40 Figure 6 represents a top plan view of the lower display shelf and brace, and

Figure 7 represents a top plan view of the combined display or advertising sign and brace.

45 Described in general terms, the invention comprises a "knock-down" cardboard rectangular receptacle stamped from a single sheet of material as shown in Figure 1. The blank is suitably cut to form front sections 1, back sections 2, end sections 3 and 4, top sections 5, bottom sections 6, locking end flaps 7 and locking top and bottom flaps 8 and 9. The divisional line 10 between the sections 6—6 and 9 is scored as is also the line 11 between sections 6—6 and 2—2 and the line 12 between sections 55 2—2 and 5—5, and also the line 13 between sec-

tions 5—5 and 8. Further the line 14 between sections 2—2 and 3—4 is also scored. A flap 15 extends from the outer end of the section 4 with a scored line 16 between. This flap 15 is a pasting flap for securing the vertical walls 1, 2, 3 5 and 4 in rectangular formation in assembling the carton for shipping.

By reference to Figures 1 and 2, it will be seen that the perforated line 17 is located between the sections 5—5, 2—2 and 6—6. The adjoining edges of these sections remain intact during shipping but after the container is received and when it is employed as a display rack, the solid portions of material between the perforations 17 are cut or ruptured whereby the sections 5—5, 2—2 and 6—6 are separated and what might be termed the two corresponding halves of the container adjusted to extend at right angles to each other as clearly shown in Figure 3. The sections 2—2, and the front sections 1 are 20 formed with double rows of perforations 18 and 19 respectively. These perforations outline slots which remain closed during the shipping of the merchandise but are cut or ruptured to open up the slots after the container is received. The 25 closure flaps 7 are all doubled inward when the carton is assembled as shown in Figure 2. After being so doubled, the connecting bottom sections 6—6 and the connecting top section 5—5 are doubled respectively over the top and bottom 30 and the flaps 8 and 9 tucked in between the edges of the sections 7—7 and the vertical back wall of the box. This forms a rectangular box which may be opened by raising the top sections 5—5 and the upper flap sections 7—7 and the box 35 filled with merchandise for shipping.

Openings 20 are formed in the blank on the line 13 as shown in Figure 1 for a purpose now described.

The sections of the display shown in Figures 5, 40 6 and 7 are enclosed within the box as formed in Figure 2 along with the merchandise and are removable with the merchandise when received.

When the shipping box is received, the contents are first removed and three sides of the box 45 are severed along the line 17. The two halves of the box are then doubled at right angles to each other, as shown in Figure 3 forming a greatly extended base for the firm support of the display. The upper shelf and brace shown in Figure 5 50 comprises a main shelf portion 21, inclined portions 22 having extension locking lugs 23 and a central bracing portion 24. When this shelf 21 is placed in position the portion 24 projects with its edge in the centrally divided slot 18 and with 55

the lugs 23 projected through the companion slots 18 in the sections 2—2. This construction holds the shelf 21 firmly in position and braces it by the extension of the portion 24 through the slot 18 at the rear.

By this means the shelf is braced against the weight of the articles placed thereon as shown in Figure 3. This peculiar formation results in a central alcove and two end shelf portions for display purposes. This is also illustrated in Figure 4.

The lower shelf 25, shown in Figure 6, is then applied to the lower portion of the assembled display with the slots 26 receiving the severed edges of the sections 2—2 and the edges 27 of said shelf resting against the sides of the sections 2. This shelf section 25 by the above construction locks the two portions of the separated halves of the box in their adjusted positions at right angles to each other. Articles may be placed on the lower shelf just as they are on the upper shelf and further assist in giving rigidity to the display and anchoring it in position.

The upper edge of the display is tied together in its adjusted position by the advertising or display sign panel 28, shown in Figure 7. This panel is provided with projecting ears 29 which are slipped through the slots 20 when the sign is applied in position, after the two halves of the box have been adjusted at right angles to each other. This results in holding the upper edges of the two halves in their adjusted relative positions and lends rigidity to the entire structure.

It will, of course, be understood that many other forms of display cards may be secured in position by lugs 29 upon the top of the display when it is set up; the length of such panels being the tie bar for securing the two halves of the box in their adjusted angular positions.

It will be understood that with the present device a completely enclosed shipping receptacle is provided in which any type of merchandise may be shipped with perfect safety.

It will also be understood that such a shipping carton with its unbroken walls is endowed with the necessary strength because of its rectangular form, but at the same time such a carton may be almost instantly completely fitted into a very attractive and rigid display stand with provision for supporting the displayed merchandise at different levels.

What I claim is:

In a shipping and display carton, the combination with a front, back, top, bottom and sides formed with partly severed walls for forming two sections that may be adjusted in angular relation to each other and having securing slits in the side walls and shelf means having projections which enter said slits to act as a tie bar and secure the shelves in position on the front of the carton and also lock the dividing sections in their angular relation to each other.

ALBERT H. KOEBLE.
